FIG. 1 is a top, frontal perspective view of a dust cleaning tool adaptive to a vacuum cleaner nozzle showing my new design;

FIG. 2 is a rear, bottom perspective view thereof;

FIG. 3 is a top plan view thereof;

FIG. 4 is a front elevational view thereof;

FIG. 5 is a side elevational view thereof;

FIG. 6 is a rear elevational view thereof; and,

FIG. 7 is a bottom plan view thereof.
